TONJES A. BOTH, OF STRATFORD, CONNECTICUT, ASSIGNOR TO THE CONNECTICUT ELECTRIC MANUFACTURING COMPANY, A CORPORATION OF CONNECTICUT.

MECHANICAL MOVEMENT.

1,327,192.

Specification of Letters Patent.

Patented Jan. 6, 1920.

Application filed July 12, 1919. Serial No. 310,333.

To all whom it may concern:

Be it known that I, TONJES A. BOTH, a citizen of the United States, residing at Stratford, county of Fairfield, State of Connecticut, have invented an Improvement in Mechanical Movements, of which the following is a specification.

This invention has for its object to provide a mechanical movement adapted for 10 general use wherever it is required to utilize either the constant or intermittent rotation or oscillation of a shaft in producing correspondingly intermittent reciprocatory movement of another member, each half 15 rotation of the shaft producing a movement in one direction of the reciprocating member, the essential feature being that no reciprocatory movement takes place until a quarter rotation, more or less, has been im- 20 parted to the shaft, and that said movement is then made with a quick snap, the completion of the half rotation of the shaft being an idle movement. This movement is applicable to various uses as in valve mech- 25 anisms, and in making and breaking the circuit in electrical devices. It is immaterial so far as the principle of the invention is concerned whether the parts are so constructed and arranged that the shaft is 30 adapted to rotate continuously in either direction, or in one direction only, or to oscillate.

With the above stated and other objects in view, I have devised the novel mechanical 35 movement which I will now describe referring to the accompanying drawing forming a part of this specification and using reference characters to indicate the several parts.

Figure 1 is an elevation of my novel 40 mechanical movement;

Fig. 2 a section on the line 2—2 in Fig. 1, looking in the direction of the arrows, the spring being partly broken away;

Figs. 3, 4, 5, 6 and 7 sections on the same 45 line illustrating different positions of parts, and

Fig. 8 is a perspective view of the actuating member, detached.

10 denotes the shaft which is provided 50 with a double crank 11. The shaft is journaled in a suitable frame, indicated by 12, which may of course be of any required construction, the crank lying between arms or branches of the frame. 13 denotes a rocker 55 which is pivoted between the arms of the

frame and itself comprises arms lying on opposite sides of the crank and each provided with a circular opening 14 through which the shaft passes. The special construction of the rocker is unimportant so 60 far as the principle of the invention is concerned. I have shown the arms of the rocker as connected at their pivot ends. Both ends may be connected if preferred and the rocker as a whole may be either 65 formed from sheet metal or cast. I preferably use a two armed rocker as it gives a better balanced construction. One arm may, however, be dispensed with and a one armed rocker used, if preferred.

Lying between the arms of the rocker is an actuating member which comprises a head 15, arms 16 and shoes 17 which are adapted to travel around the walls of the circular openings in the arms of the rocker. 70 Lying between the arms of the actuating member is a coil spring 20, one end of which bears against head 15 and the other against the pin 18 of the double crank, which lies between the free ends of arms 16.

Each half rotation of the shaft causes the crank pin to carry the actuating member around with it, the crank pin at the same time moving inward between arms 16 and compressing the spring, and then outward 85 again when the tension of the spring is relieved, the shoes meanwhile traveling around the circular walls which bound the openings in the arms of the rocker.

The special connections by which the oscillations of the rocker are utilized in producing intermittent reciprocatory movement wherever required in a mechanical structure are unimportant as far as the principle of the invention is concerned. In the present 90 instance I have indicated that the connection may be made by means of a forked link 19 connected to the arms of the rocker.

The operation is as follows: The invention 100 is equally operative if the shaft is rotated clockwise, or counter-clockwise, or oscillated starting with a clockwise, or a counter-clockwise movement. Starting with the parts in the position shown in Figs. 1 and 2, I will describe the operation when 105 the shaft is rotated continuously in the clockwise direction. In Fig. 3 the parts are on the dead center, the pivotal point of the rocker, the axis of the spring and the crank pin being in alinement, and the 110

spring fully compressed by the inward movement of the crank pin between the arms of the actuating member. An instant later the dead center will have been passed, 5 the tension on the spring relieved, and the spring will instantly throw the parts to the position shown in Fig. 5, the position in Fig. 4 being an intermediate position showing the spring expanding and forcing the 10 crank pin outward between the arms of the actuating member. In practice the movement from the position in Fig. 3 to that in Fig. 5 is instantaneous, the spring causing the actuating member, and with it 15 the rocker, to jump ahead of the shaft with a snap, and the last quarter rotation, more or less, of the shaft being an idle movement. Continuing the movement of the shaft, Fig. 6 shows a position of the parts an instant 20 after the dead center has been passed the second time, the spring being at its fullest compression and about to expand, the movement of the rocker not having commenced. Fig. 7 shows an intermediate position of 25 the parts, in other words, a position of the parts in the second half rotation corresponding with the position in the first half rotation shown in Fig. 4. An instant later the parts will be in the position shown 30 in Fig. 2, a rotation of the shaft having been completed, and a complete reciprocation of the rocker having been produced. The throw of the rocker is determined by the size of the opening or openings in the 35 rocker through which the shaft passes, alternate opposite sides of the walls of the openings contacting with the shaft after the movements. These movements are continuously repeated, each rotation of the 40 shaft producing a complete reciprocation of the rocker and the movement of the rocker in each direction being made with a snap, jump or kick through the expansion of the spring the instant the parts have 45 passed the dead center. Incidentally it may be noted that while the compression of the spring is the same in the first portion of each half rotation of the shaft the full compression of the spring is reached and 50 the parts are at their dead center slightly earlier when the crank pin is approaching the pivotal point of the rocker *i. e.* in the second half rotation of the shaft, than when the crank pin is moving away from the 55 pivotal point of the rocker. This, however, is wholly immaterial so far as the principle of the invention is concerned.

Suppose now that the shaft is oscillated 60 making half rotations in each direction and starting in the clockwise direction. The movement, as shown in Figs. 3 and 4, to the position in Fig. 5, would be as before, and on the return movement the movement would be as shown in Figs. 4 and 3 to that 65 shown in Fig. 2. This half rotation of the

shaft and back to its starting position would have produced a complete reciprocation of the actuating member as before.

Should the shaft be rotating counter-clockwise, the movement would be from the 70 position shown in Fig. 2 through the positions shown in Figs. 7, 6, 5, 4 and 3 to that in Fig. 2.

Should the movement of the shaft be oscillatory starting in the counter-clockwise 75 direction the movement would be from Fig. 2 through Figs. 7 and 6 to that in Fig. 5 and then backward through the positions shown in Figs. 6 and 7 to the position in Fig. 2.

Having thus described my invention, I 80 claim:

1. A mechanical movement comprising a rocker pivoted at one end and provided with a circular opening, an actuating member consisting of a shoe which engages said opening, a head and arms, a crank having a pin lying between the arms, and a spring bearing against the head and the crank pin, movement of the crank causing the shoe to 85 travel around the opening without imparting movement to the rocker, and causing the crank pin to move inward between the arms and compress the spring until the parts are on a dead center, continued movement of the crank causing the spring to 90 expand instantly and the actuating member to throw the rocker to the extreme of its movement with a snap.

2: A mechanical movement comprising a 100 rocker having a circular opening, an actuating member having a shoe which engages said opening, a crank having a pin engaging the actuating member, and a spring carried by the actuating member and bearing 105 against the crank pin, movement of the crank causing the pin to compress the spring and the expansion of the spring causing the actuating member to move the rocker with a snap.

3. A mechanical movement comprising a 110 rocker having an opening, an actuating member comprising arms and a shoe adapted to travel about the opening, a crank pin between the arms, and a spring lying 115 between the arms and bearing against the crank pin, the pin acting to compress the spring until the dead center is reached, the spring then causing the actuating member to throw the rocker to the extreme of its 120 movement.

4. A mechanical movement comprising a 125 rocker having an opening, an actuating member having a shoe adapted to travel about said opening, a crank pin engaging the actuating member, and a spring carried by the actuating member and bearing against the crank pin.

5. A mechanical movement comprising a 130 rocker having arms each provided with a

5 circular opening, an actuating member consisting of a head, arms, and shoes engaging said openings, a double crank having a pin lying between the arms and a spring bearing against the head and the crank pin.

10 6. A mechanical movement comprising a rocker, a pivot at one end on which the rocker swings, said rocker consisting of arms, each having a circular opening, an actuating member having shoes engaging said openings, a crank pin engaging the actuating member and a spring carried by the actuating member and bearing on the crank pin.

15 7. A mechanical movement comprising a rocker having arms provided with circular openings, an actuating member having shoes engaging said openings, a crank pin engaging the actuating member, and a spring carried by the actuating member and bearing against the crank pin.

20 8. A mechanical movement comprising a rocker having a circular opening, an actuating member having a shoe adapted to travel about said opening, a shaft passing through said opening, a crank on said shaft having a pin engaging the actuating member, and a spring carried by the actuating member and bearing against the crank pin, rotation of the shaft causing the pin to compress the spring, and expansion of the spring causing the actuating member to move the rocker with a snap, the size of the opening through

which the shaft passes determining the throw of the rocker. 35

9. A mechanical movement comprising a rocker having arms provided with circular openings, an actuating member having shoes adapted to travel about said openings, a shaft passing through said openings, a 40 double crank on said shaft having a pin engaging the actuating member, and a spring carried by the actuating member and bearing against the pin.

10. A mechanical movement comprising a 45 rocker pivoted at one end and having arms provided with circular openings, an actuating member consisting of shoes adapted to travel about said openings, and arms, a shaft passing through said openings, a double crank on said shaft having a pin lying between said arms, and a spring carried by the actuating member and bearing against the crank pin. 50

11. A mechanical movement comprising a 55 rocker having openings, an actuating member having shoes engaging said openings, a shaft passing through the openings and having a crank engaging the actuating member and a spring carried by the actuating 60 member and bearing against the pin of the crank.

In testimony whereof I affix my signature.

TONJES A. BOTH.
